UNITED STATES PATENT OFFICE.

CHESTER H. THORDARSON, OF CHICAGO, ILLINOIS.

RHEOSTAT.

Application filed October 20, 1922. Serial No. 595,732.

This invention relates to improvements in rheostats for regulating or adjusting an electrical circuit and refers more particularly to an improvement in a contact member which is adapted for wiping engagement with the coils of the rheostat winding, and preferably of that type in which the winding is part cylindric and of oblong cross section and in which the contact member wipes over the inner face of such winding.

The present improvements are shown in connection with a vernier rheostat such as shown in my prior application for United States Letters Patent No. 562,607, filed May 15 28th, 1922, but may be applied to single winding or one-stage rheostats.

The present invention relates more specifically to, and is an improvement on, the contact member of the main arm of the rheostat element which is so constructed and arranged, in accordance with the present invention, as to provide a wide area of contact between it and the coils of the rheostat winding; which has large current carrying capacity to avoid overheating of the contact member; which can be made at less cost and is easy to assemble, and which contact member is so constructed and arranged that within itself and in its co-operation with its arm, as to be resilient to effect a good brush contact between it and the coils of the rheostat, and to provide for irregular surfaces on the winding.

In the drawings:

Figure 1 is a plan of a rheostat embodying my invention.

Figure 2 is an enlarged plan view of the main rheostat arm and its contact member showing the latter partially in section.

Figure 3 is an edge view of said arm with the contact member shown in section.

Figure 4 is a perspective view of said contact member.

As shown in the drawings, 10 designates a winding which constitutes the principal part of a vernier rheostat circuit, 11 a relatively short or fractional part of said circuit, 12 the main conducting arm of the rheostat whose contact member travels against the inner sides of the coils of winding 10, and 13 designates the auxiliary or fractional conductor arm which is electrically connected to the arm 12 and travels along the fractional rheostat element or conductor 11.

The winding 10 is wound about and supported by an upstanding rim 14 which is fixed on the base 15 of the rheostat by the overlapping of the ends of the open rim with a lug 16 fixed to the base. 17, 18 designate binding posts by which the rheostat circuit is connected to the wires of an external circuit.

Referring now to the elements and combination of elements which constitute the present invention, the same are made as follows:

The arm 12, which may be made of sheet metal, is provided at one end with an opening 19, through which extends one of the operating shafts (not shown), and is provided at its other end with a reduced extension 20. Said extension is shown as extending centrally from the end of the arm 12 and forms at the base of the arm 20 transverse shoulders 21. The tongue or extension 20 is widened at its base to produce a rivet member 20' for a purpose hereinafter to be described.

22 designates a contact member which is fitted on the arm 12 and is adapted for brush contact with the coils of the winding 10. Said contact member is made of a single piece of resilient sheet metal which possesses a good co-efficient of current conductivity. The said contact member can be made from a metal strip of equal width throughout its length, and is provided at its end with slots, 23, 24 through which the arm extension 20 is adapted to extend. It is necessary that the contact member be connected to said arm extension in a manner to hold it firmly thereon, and for this purpose the slot 23 is made to fit flat against the shoulder 21 and over the rivet member 20' which latter is swaged at 20° over the outer face of the contact member around the opening 23 therein. Preferably the said slot and said rivet member are oblong.

The strip constituting said contact member is bent to produce a loop formation wherein the terminals 25, 26 thereof are closed in overlapping but spaced relation upon each other. The intermediate portion of said strip is curved to produce a wiping or brush face 28, which engages the sides of the coils of the main winding 10 of the rheostat circuit, the curvature of said intermediate portion of the strip being such as to provide a brush wiping contact thereof.

with the inner sides of said coils. The said contact member is made of substantial depth, when used in connection with the form of winding illustrated in my aforesaid application, so that the engagement between the contact member and the coils of said winding will be throughout the width of the wiping curved portion 28 of the contact. This construction of the contact member 10 gives not only a good contact between it and the coils of the main rheostat winding, but also affords a large current carrying capacity at the point where the contact member engages the winding so as to thereby avoid 15 overheating of the contact member and winding at their points of contact. It is within the spirit of the invention, as herein claimed, however, to employ the resilient contact member with other forms of rheostat 20 windings.

The said aperture or slot 24 is made longer than the width of the arm extension 20 so that the free end or terminal 26 of the contact member can move freely relatively 25 to the said tongue or extension, and thereby give ample freedom of adjustment to the resilient contact member to adapt itself to the inner face of the main winding. Furthermore the self contained resiliency of the 30 outer looped portion 28 of the contact member permits said member to yield inwardly after the free end 24 is brought up against the terminal 25, and until said brush portion is sprung inwardly into contact with 35 the end of the tongue 20, which constitutes the final limit of resilient movement of the contact member. It will thus be seen that the flexibility of the contact member is produced both by the resiliency of the metal of 40 which it is formed and by the slight freedom of movement afforded by the elongated slot 24. The limiting stop formed by the end of the tongue or extension 20 prevents the curved brush portion of the loop contact 45 member from being bent so far inwardly as to cause it to tend to take an inward set, should undue force be applied to the brush face of said member at a time when the arm 12 is removed from the connection to the 50 rheostat structure.

An advantage of the construction shown is that the contact member 22 described, and its co-operation with the arm 12, affords a wide face bearing between said contact member and the coils of the winding, and a contact which will be firm by reason of the 55 pressure due to the inherent resiliency of the metal forming the contact member and its anchorage connection to the arm. It will be furthermore noted that a defective con-

tact member can be readily removed and a new one placed on the arm.

I claim:

1. A resilient contact member for the conducting arm of a rheostat made of open 65 looped formation to provide an intermediate curved brush surface, the ends of said loop being folded back on each other and provided with registering apertures.

2. A resilient contact member for the con- 70 ducting arm of a rheostat made of open looped formation to provide an intermediate curved brush surface, the terminals of said loop being folded back on each other in overlapped, spaced relation and said terminals being provided with apertures to engage over a support to which one of the terminals is attached.

3. A resilient contact member for the con- 80 ducting arm of a rheostat made of open looped formation to provide an intermediate curved brush surface, the terminals of said loop being folded back on each other in overlapped, spaced relation and said terminals being provided with apertures to engage over a support to which one of the terminals is attached, the aperture of the other terminal fitting loosely over said support.

4. A contact device comprising an arm, 90 and a looped resilient contact piece extending across an end of said arm and confined to the arm at both ends to permit relative limited movements between said arm and at least one end of said contact piece.

5. A contact device comprising an arm and 95 a looped resilient contact piece extending across the end of said arm, one of the ends of said contact piece being fixed to the arm and the other end being secured to the arm to permit limited relative movements be- 100 tween the same and the arm.

6. A contact device comprising an arm provided with a reduced extension at one 105 end forming an outwardly facing shoulder, and a resilient looped contact member having a curved intermediate contact face and provided at its ends with slots engaged over said extension.

7. A contact device comprising an arm provided with a reduced extension at one 110 end forming on the arm an outwardly facing shoulder, a resilient looped contact member having slots in its ends through which said extension passes, said extension fitting into one of said slots and being loose in the other 115 slot.

In witness whereof I claim the foregoing as my invention, I hereunto append my signature this 12 day of October, A. D., 1922.

CHESTER H. THORDARSON.
